UNITED STATES PATENT OFFICE.

GEORGE A. SPANG, OF BUTLER, PENNSYLVANIA, ASSIGNOR TO SPANG AND COMPANY, OF BUTLER, PENNSYLVANIA, A CORPORATION OF PENNSYLVANIA.

METHOD OF MAKING JARS.

Application filed August 12, 1921. Serial No. 491,848.

This invention relates to a new and improved method of manufacturing jars.

An object of the invention is to produce jars which are stronger and less liable to break while in operation than those now in use and known to me.

A further object is to produce jars in which each co-operating member forming a part of the jar is formed in one piece with no welded or other joints.

A further object is to produce jars in which the co-operating or interlinked members are both formed from a single piece of metal.

These and other objects which will be made more apparent throughout the further description of the invention are attained by means of apparatus embodying the features herein described and illustrated in the drawings accompanying and forming a part hereof.

Fig. 1 illustrates an initial step in the operation of forming jars by means of a forging process herein described. Figs. 2, 25 3 and 4 illustrate successive steps in the process, and Fig. 5 illustrates the finished jars. Fig. 6 is a sectional view along the line 15—15 of Fig. 3 and Figs. 7 and 8 are sectional views on the line 7—7 of Fig. 1 taken 30 at different steps in the operation of the method herein described.

During the last decade steel has been greatly improved, primarily because of the discovery that certain steel alloys have 35 greater strength and durability than steel free of the alloying metal. Most of the mechanical arts have profited by this discovery, but, heretofore, it has been impossible to employ steel alloys, having the desirable characteristics of strength and durability, in the manufacture of jars, due to the fact that it is impossible to obtain a satisfactory weld with such steel alloys and due also to the fact that the peculiar construction of jars has heretofore rendered it impossible to manufacture jars without welding or without providing some kind of a joint in at least one of the interlinked members.

A primary object of my invention is the production of a method of manufacturing jars in which steel alloys having the desirable characteristics may be employed.

My invention consists essentially in so

forming the interlinking members of a set 55 of jars that both members are completed without the necessity of providing them with a welded or any other kind of joint. As will be more fully described, this is accomplished by forming the two interlinked 60 members so that each member is formed and completed interlinked with its co-operating member.

In the process herein described the inter-linked members are so formed that the striking heads are integrally connected by the metal of the intermediate portion of the bar. Prior to the final steps of the method employed in completing the jars, this intermediate or connecting metal is severed in 70 such a way as to free the interlinked members without disengaging them from their interlinked association. In Figs. 1 and 2, I have illustrated two steps in the process of forming the jars. An initial step consists 75 in shaping the bar so that its external surface approximates the contour of the finished jars.

The metal bar is then forged in such a way as to form a slot 16, as shown in Fig. 80 ure 1. The forging operation in forming this slot roughs out the reins 17 of one inter-linked member and the fishtail 18 of the other interlinked member. It will, of course be understood that the actual forging opera- 85 tion leaves a flash in the slot 16 which must later be removed. The bar is then turned end for end a quarter turn about its longitudinal axis for the purpose of completing the preliminary step of forming the reins 90 and fishtails of the two interlinked members, by forging a slot 16^a as shown in Fig. 2 and thus roughing out the reins 18^a and fishtails 17^a of the other interlinked member. During this forging operation the same dies 95 are preferably employed for forging both ends of the bar and the bar is preferably so placed in the dies during the second forging operation that the portion of the reins and fishtails partially completed by the first 100 operation are located in the dies during the second operation for the purpose of guiding the second forging operation. In other words, more than half the interlinked elements are formed by the first forging opera- 105 tion so that the second forging operation overlaps that of the first.

It will be apparent that two distinct sets

of dies may be employed in the forging operation and that by properly designing the dies and by properly locating the metal bar in the dies, both ends of the bar may be 5 simultaneously forged for the purpose of partially completing both interlinked members. This could be accomplished by so forming each die that the plane of cleavage between the two dies is so located with relation to the jars to be formed that it is extended at an angle to the planes defined by the lateral surface of each pair of reins. The method herein described is, however, simpler because the dies are simpler and the 15 forging operation can be accomplished with a minimum flow of metal.

The flash or thin web of metal between the reins and fishtails, formed by this forging operation, is then removed by shearing, or 20 in any other desired manner. It will be apparent that the slot 16^a extends from the intermediate portion 20 in a direction opposite to that of the slot 16. As above mentioned, the forming of the slot 16 roughs out the 25 fishtail 17^a, forming an integral part of the reins 17 and it also roughs out the reins 18^a forming an integral part of the fishtail 18. This slot forming operation roughs out the crutch 21 of each interlinked member by 30 reason of the fact that each pair of reins merges into one of the squares 22 of the jars and the formation of the reins necessarily forms the crutch. Another feature of the slotting operation is that the slots extend in 35 both directions from a point intermediate the ends of the bars. In Fig. 7 I have illustrated, in cross section, the unslotted portion of the bar. It will be apparent that the proximity of the adjacent ends of the slots 40 16 and 16^a will determine, to some extent, the throw or stroke of the jars, although this may also be controlled by varying the distance between the end of each fishtail and its co-operating crutch at the time of milling 45 the slots in the bar. After the slots are milled the intermediate metal is then broken for the purpose of freeing the interlinked members.

In Fig. 8 I have shown one way of preparing the bar for breaking or severing this metal. It consists essentially in reducing the sectional area of the metal connecting the two interlinked members by drilling 50 holes 23 therethrough. As shown, 4 holes are drilled at right angles to each other for the purpose of blocking out the intermediate portion of metal. Diagonal holes are then drilled for the purpose of weakening the blocked out section. Any means may be employed for breaking or severing the metal at the weakened section and for thereby freeing the interlinked elements from each other. It will be apparent that the blocking out of the subsequently weakened section reduces 55 the tendency of the reins to break or crack

when the weakened section is broken since the blocking out process relieves the reins of the strain and prevents the fracture extending into the reins or fish-tails. It will be apparent that the interlinked lapping elements are disconnected or broken apart in such a way as to increase the stroke of the jars over that provided by the slotting operation. This is accomplished by slotting as 60 shown in Figs. 1 and 2 so as to leave an unslotted portion of appreciable length between the adjacent ends of the two slots and by then drilling two sets of weakening holes through this unslotted intermediate portion, one set being located adjacent the end of the slot 16 and the other set adjacent the end of the slot 16^a. Under such conditions, the 65 operation of severing the interlinked members frees a block of metal, the permissible size of which is determined by the clearance between the reins of the two interlinked members, since it is necessary to remove this block before the jars are finally completed.

The partially formed members are then 70 turned at an angle to each other or to the position shown in Fig. 3 and the reins of each member are partially compressed so that they may be introduced into co-operating dies, such as illustrated in Fig. 4. Each member is then forged for the purpose of 75 producing the reins, fishtails, crutches and rein courses, and this forging operation reduces the section of the fishtail to substantially that illustrated in Fig. 6, in which the 80 rein courses 25 are clearly illustrated.

After each element is so formed they are 85 turned to the positions illustrated in Fig. 5, that is, to a position in which the longitudinal axes of both interlinked members are co-incident and the final operation of forming the reins and fishtails is performed by 90 pressing the reins of each interlinked element to the positions illustrated in Fig. 5. During this operation, the previously formed 95 fishtails and crutches are, of course, deformed and the previous finishing operation must be performed in such a way as to compensate for the deformation occasioned by 100 the final pressing operation. It will be apparent that the forging of the boxes and pins, 105 as well as the squares, may be done at any convenient time and that the boxes and pins may be threaded at any convenient time during 110 the process of manufacturing the jars. It will also be apparent that jars so manufactured may be heat treated and tempered in the usual manner or in the manner best suited to the metal employed in their manufacture.

Various changes, additions, modifications 115 and omissions may be made in the process herein described without departing from the spirit and scope of the invention as set forth by the appended claims.

I claim:—

1. A process of manufacturing jars, which consists in forming the interlocking members in interlinked position, turning the interlinked members so that their longitudinal axis are at an angle, separately shaping the striking heads of the interlinked members while the members are so turned, then turning the members so that their longitudinal axes are aligned and finally shaping the 10 reins of each member so that they co-operate with the reins of the other member in guiding the relative motion of the interlinked members. 50
2. A method of manufacturing jars which 15 consists in forming the interlocking members in interlinked position and connected together, severing the connection between the members so that they are retained interlinked, moving the interlinked members out 20 of alignment with each other, then in separately shaping the striking heads of each member and finally shaping the reins of each member while the members are aligned so that they co-operate with the other member. 55
- 25 3. A process of manufacturing jars, which consists in forming the interlocking members in interlinked position, turning the interlinked members so formed out of alignment, separately shaping the striking heads and rein courses of each member while the members are turned out of alignment, placing the members in alignment, and finally 30 shaping the reins of each member so that they form a guide for the other member. 60
- 35 4. A method of manufacturing jars, which consists in forging one end of a metal bar to 40 form a portion of each of the interlocking links, then completing the formation of both links by forging the other end of the bar so that the two forging operations overlap at the central portion of the bar, so severing the interlocking members so formed 45 that they are retained interlinked, turning the interlinked members out of alignment, separately shaping the fish tails of each member by a forging operation while the members are turned out of alignment, and in 55 finally shaping both members while in alignment. 60
5. A method of forming the interlinked members of drilling jars, which consists in forging one end of a metal bar to partially form both members, forging the opposite end to completely form both members in interlinked position, separating the members so formed while maintaining them in interlinked position, turning the members so formed out of alignment and then separately forging each member while it is out of alignment and interlinked with the other. 65
6. A method of forming the interlinked members of a drilling jar from a single bar of metal, which consists in forging the bar to partially form the reins and striking heads of both members, severing the metal connecting the members while maintaining them in interlinked position, moving the interlinked members so formed out of alignment, and separately forging the fish tail and rein courses of each member while out of alignment and interlinked with the other, then moving the interlinked members back 70 into alignment and pressing the reins of each member into co-operative relation with the rein courses of the other member. 75
7. A method of forming the interlinked members of a drilling jar from a single bar of metal, which consists in forging the bar to form the reins and striking heads of both members, with the reins of each member spread apart, severing the metal connecting the members so formed while maintaining the members in interlinked position, moving the interlinked members out of alignment, separately shaping the fish tail and rein courses of each member while out of alignment and interlinked with the other member, moving the interlinked members into alignment and pressing the spread reins of each member into co-operative relation with the rein courses of the other member. 80
- 85 In testimony whereof, I have hereunto subscribed my name this 8th day of August, 1921. 90

GEORGE A. SPANG.
